WINDOW OPERATING MECHANISM

William W. Fuller, Norfolk, Va.

Application February 26, 1934, Serial No. 713,033

6 Claims. (Cl. 268—124)

This invention relates to means for raising and lowering the sash of windows and whereby motor driven means are connected to the upper and lower sash of windows so that either the upper or lower sash can be raised or lowered selectively from one motor.

It is an object of this invention to provide a hollow shaft threaded on its exterior and having engagement with one of the window sashes for raising and lowering the same and to provide a threaded rod disposed within the hollow shaft and having threaded engagement with the other sash for raising and lowering the same and a motor adapted to be selectively connected to each of these shafts for selectively raising or lowering the sashes of the window. The mechanism is applicable to any window sash without the necessity of reconstruction of either the window sashes or the window frame.

It is another object of this invention to provide a pair of shafts threaded on their exterior and engaging threaded means attachable to the upper and lower sashes of a window and having motor driven connections for driving these shafts for raising and lowering the window sashes and also having safety means whereby when a window sash has been raised or lowered to a predetermined extent the motor will be automatically stopped.

Some of the objects of the invention having been stated, the details will appear more fully when taken in connection with a detailed description hereinafter following, reference being had to the drawing, in which:

Figure 1 is an elevation of a window with my sash operating mechanism attached thereto;

Figure 2 is a sectional plan view taken along the line 2—2 in Figure 1;

Figure 3 is a vertical sectional view taken along line 3—3 in Figure 2;

Figure 4 is a schematic wiring diagram showing the method in which the motor is wired;

Figure 5 is a view showing another means for connecting the sash arms to the threaded rods;

Referring more particularly to the drawing, the numerals 10 and 11 denote the conventional jambs of a window frame which have secured at their upper ends a head portion 12 and at their lower ends a sill 13. Mounted in this frame are sashes 14 and 15. Heretofore, sashes 14 and 15 have been raised and lowered by various means such as weights and cords and it is an object of this invention to provide a purely mechanical means which will automatically raise or lower

the window sashes upon the manipulation of a suitable switch.

Secured to the upper sash is a suitable arm 16 by any suitable means such as screws 17. This arm projects to the right in Figure 3 and has an 5 interiorly threaded bore in the right-hand end thereof which is adapted to threadably engage a vertically disposed rod 18, said rod 18 being rotatably mounted at its upper end in a suitable bearing 19 which is secured to the window head 10 12 by any suitable means such as screws 20. Rod 18 projects downwardly and is rotatably secured at its lower end in housing 21. The lower sash 14 has secured thereto by screws 25 an arm 26 which is adapted to engage rod 27. The right- 15 hand end of arm 26 is similar in all respects to the right-hand end of arm 16 and has an interiorly threaded bore which is adapted to engage the threaded portion 30 on rod 27. Rod 27 is confined around the lower portion of rod 18 and 20 is adapted to rotate therearound.

Loosely mounted around the central portion of rod 18 is a coil spring 31 which is adapted to press the arm 16 upwardly when the upper sash is in lowered position. It is evident that when the 25 right-hand end portion of arm 16, which engages the threaded portion 32 of rod 18, is lowered it will rest upon the spring 31. Since spring 31 will normally press the arm upwardly the threaded bore in the right-hand portion of the 30 arm 16 will contact the threaded portion 32 at all times. When the motor is reversed in this position the threaded portion 32 will engage the interiorly threaded portion of arm 16 and therefore the window will be raised.

The construction of the lower rod 30 is similar in all respects to upper rod 18. It will be noted that the central portion of the rods 27 and 30 are threaded whereas the upper and lower portions are blank. When the threaded portion of arm 40 26 reaches the uppermost portion of rod 27 where there are no threads the sash 14 will be raised in its uppermost position and the weight of the sash will normally force the threads in the right-hand portion of arm 26 against the threads of rod 27 45 and by reversing the direction of the motor the threads on the rod will engage the threads in arm 26 and the window will be lowered.

In the lowermost position as shown in Figure 3, of the sash 14 the arm 26 engages a collar 33 50 which is secured around pipe 34 by any suitable means such as set screw 35. Pipe 34 is slidably mounted at its upper end in member 19 whereas at the lower end a receptacle is provided. The upper portion 19 has mounted therein a compres- 55

sion spring 37 which normally forces the pipe 34 downwardly whereas the receptacle 38 which is integral with the housing 21 has mounted therein another compression spring 38 which forces the pipe upwardly. By having spring 38 of sufficient strength to push the sash and pipe upwardly, it is evident that when the arm 26 engages the collar 33 that the sash will be normally pushed upwardly which will cause the threaded portion of arm 26 to be pushed against the threaded portion 30 of the rod 27 at all times. In the position shown in Figure 3, if it is desired to raise the lower sash by reversing the direction of rotation of the rod the threads in arm 25 will readily engage the threads on rod 27.

It should be noted that pipe 34 is slotted on the inside adjacent the window sash the entire length for the purpose of allowing the arms 16 and 26 to have vertical movement. Also mounted on pipe 34 are collars 41, 42 and 43 by any suitable means such as set screws 41a, 42a and 43a. By adjusting these collars in the desired position the motor switch can be automatically cut off when the window has been raised to the desired position. Collars 41, 42 and 43 as well as collar 33 operate the switch mechanism which will be later described.

The lower end of rod 27 has fixedly secured thereon a gear 44 whereas the lower end of rod 18 has a similar gear 45 fixedly secured thereon. These gears are adapted to mesh with another gear 47 which is fixedly secured on rod 46, said rod 46 being mounted in the housing 21. Adapted to mesh with gear 47 is a smaller gear 48 which is also mounted in housing 21 and this gear meshes with another gear 50 mounted on motor shaft 49.

Housing 21 is divided into two portions 21a and 21b, the portion 21b being removable for inspection of the gears on the inside thereof. The lower portion 21a is adapted to fit over the motor housing 51 as at 52, and by referring to Figure 2 it can be seen that the housing 21 and the window operating means associated therewith are adapted to have pivoted movement about the point 52. This will allow adjustment of the window operating mechanism to any desired depth of window sill without affecting the structure in any way.

Motor housing 51 is secured to the window sill 13 by any suitable means such as screws 52a and on the interior of the motor housing is mounted a motor 53 as at 54. Collar 33 has integral therewith a horizontally disposed arm 56 which penetrates a collar 57.

A set screw 58 penetrates collar 57 and secures the rod 56 in the collar 57 in any desired position. The length of rod 56 will vary slightly when the housing 21 and the pipe 34 are rotated, therefore, by using the screw 58 and the sliding fit between the rods 56 and the collar 57 the adjustment as to the effective length of arm 56 can be made after the upper portion 21 and its associated parts have been secured to the window. When portion 21 is secured to the window sill as at 60 the necessity for the adjustment of rod 56 in collar 57 will be no longer necessary after it has been once adjusted. Secured to the collar 57 is a vertically disposed rod 61 which projects downwardly through the motor housing 51 and the lower end is slidably mounted in lug 62 within the motor housing. A spring 64 is confined between the lug 62 and nut 63 on the lower end of rod 61, whereas another spring 65 is confined above the lug 62 and is held in position by collar 66 secured to rod 61.

Pivotedly secured to collar 66 is a flexible mem-

ber 67 and this member 67 is secured to switch 68 which is pivoted as at 69. Referring to Figure 3, it is evident that springs 64 and 65 normally hold the switch in open position. For example, when it is desired for the motor 53 to rotate in one direction the switch arm 68 is pushed downwardly, and the wires 71 and 71a are connected to wires 73 and 73a.

Since the member 67 is flexible the switch can be manually closed and upon the contact of these wires the circuit will be completed and the current will flow through wires 71 and 73, motor 53, field coil 74, wire 73a and wire 71a. If it be desired to reverse the direction of the motor from that just described, the wires 70 and 70a will be caused to contact the wires 72 and 72a. In this position the current would flow through wire 70, wire 72, field coil 74, motor 53, wire 72a and wire 70a.

As has been previously stated, the collars 41, 42 and 43 may be located at any suitable position along the pipe 34 and should it be desired to raise the lower sash only partially open, the collar 33 would be lowered from the position shown in Figure 3. In this position when arm 26 would engage collar 43 the pipe 34 would be moved upwardly a slight distance carrying with it the arm 56 and the vertically disposed rod 61. This slight upward movement of rod 61 would move the flexible member 67 upwardly and cause the right-hand portion of switch 68 to be moved downwardly to open position as shown in Figure 3. This action is based on the assumption that when it is desired to raise the sash, the right-hand end of the switch is moved upwardly and when the sash is lowered the right-hand end of the switch is moved downwardly thereby making contact between either wires 70, 70a and 72, 72a or wires 71, 71a and 73, 73a.

It is seen that when arm 68a is rotated in a clockwise direction about point 68 by the movement of rod 61, the contact between wires 70 and 72 and 70a and 72a will be broken. In like manner when the window is lowered, arm 26 contacts collar 33 and pushes rod 61 downwardly. This will break the connection between wires 71 and 73 and 71a and 73a since arm 68b will be rotated in a counter-clockwise direction.

Rod 46 which has gear 47 mounted thereon is adapted to be moved upwardly or downwardly, depending upon which sash will be operated.

If the lower sash is to be operated, the gear 47 is pulled upwardly and caused to mesh with gear 44. In like manner, if the lower sash is desired to be operated, rod 46 is pushed downwardly and gear 47 will mesh with gear 48. It is thus seen that by having a reversible switch on motor 53 and by having rod 46 with gear 47 thereon that the upper or lower sash can be moved up or down as desired, and by spacing collars 41, 42 and 43 the switch can be actuated and the motor stopped automatically when the window has reached any desired position.

It will be noted that by observing Figure 3, that the lower end of pipe 34 has a plug 80 threadably mounted therein in which is rotatably mounted the lower portion of rod 27. A collar 81 disposed immediately beneath plug 80 and being fixedly secured on the restricted portion of rod 27 causes rod 27 to be integral with pipe 34; consequently any vertical movement of rod 27 will be transferred to pipe 34, arms 56, rod 61 and switch 68. Let us suppose that collars 41, 42 and 43 are in the position shown in Figure 3, but the lower sash 14 has been raised until arm 75

26 engages the center of the threaded portion 30, and in this position the switch 68 is pulled downwardly and the upper sash 15 begins to be lowered. When the arm 16 of the sash 15 contacts the upper portion of sash 14, the arm 26 will move rod 27 and pipe 34 downwardly a slight amount which in turn will cause members 56 and 61 to actuate switch 68 to cut off the motor. It is thus seen that when the collars 41, 42 and 43 are not properly located that the motor will automatically cut off when one sash engages another. Since collar 82 is fixedly secured to the lower end of shaft 18, it is seen that should the upper sash 15 be lowered until arm 16 engages the center of threaded portion 32 and at that time the lower sash be raised by the motor when the upper portion of sash 14 contacted arm 16, rod 18, collar 82, rod 27 and pipe 34 would also be raised to cause the switch to be automatically cut off.

If desired, the arms which connect the sashes with the threaded rods may be divided into two pieces as shown in Figure 5. In this figure, arm 16a is fastened to an interiorly threaded nut 15 by means of set screws 75a, which makes the structure easier to assemble or dismantle.

In the drawing specification there has been set forth a preferred embodiment of the invention, and although specific terms are employed, they are used in a generic and descriptive sense only, and not for purposes of limitation, the scope of the invention being set forth in the appended claims.

I claim:

35 1. Means for raising and lowering the sashes of windows comprising a vertically disposed tubular member having threads on its exterior, a bracket secured to one sash and threadably engaging the threads on said tubular member, a pinion on the lower end of the tubular member, a threaded shaft disposed within said tubular member, a pinion on the lower end of the shaft, a bracket secured to the other sash and threadably engaging said shaft, a vertically movable pinion selectively engageable with one of said pinions at a time, an electric motor for driving said vertically movable pinion, a switch for controlling the motor, and resilient means for permitting vertical movement of the shaft and tubular member when undue strain is applied thereto, and means operable by vertical movement of the shaft and tube for opening said switch.

2. Means for raising and lowering the sashes of windows comprising a vertically disposed tubular member having threads on its exterior, a bracket secured to one sash and threadably engaging the threads on said tubular member, a pinion on the lower end of the tubular member, a threaded shaft disposed within said tubular member, a pinion on the lower end of the shaft, a bracket secured to the other sash and threadably engaging said shaft, a vertically movable pinion selectively engageable with one of said pinions at a time, a motor for driving said vertically movable pinion, a slotted pipe surrounding said shaft and tubular member and having

means engageable by said brackets for moving the pipe and having means operable thereby for stopping the motor.

3. Means for raising and lowering the sashes of windows comprising a vertically disposed tubular member having threads on its exterior, a bracket secured to one sash and threadably engaging the threads on said tubular member, a pinion on the lower end of the tubular member, a threaded shaft disposed within said tubular member, a pinion on the lower end of the shaft, a bracket secured to the other sash and threadably engaging said shaft, a vertically movable pinion selectively engageable with one of said pinions at a time, a motor for driving said vertically movable pinion, a switch for controlling said motor and means engageable by said brackets for opening said switch when the sashes have been moved a predetermined amount.

4. Means for lowering and raising window 20 sashes comprising a vertically disposed tubular member having threads on its exterior and a threaded shaft disposed within the tubular member, the tubular member and the shaft having each a pinion on the lower end thereof, means secured to each of the sashes and secured respectively to the tubular member and the shaft, a pinion mounted for vertical sliding movement to selectively engage the pinion on the shaft and the tubular member, an electric motor having a 30 driving connection with said vertically sliding pinion, switch means for selectively causing the motor to turn in one of two directions and means controlled by the movement of the sashes for opening said switch when either of the sashes 35 have been moved to a predetermined position.

5. Means for lowering and raising the sashes of a window comprising a fixture adapted to be secured to the central upper and lower portions of a window frame, said fixture having a threaded 40 tube and a threaded rod disposed within the tube, brackets on the sashes threadably engaging said rod and tube, a motor for imparting movement, one at a time, to said rod and tube, means for selectively connecting the motor to the rod or 45 tube, a switch controlling said motor and means operable by said brackets for opening said switch and stopping the motor when the sashes have reached an open or closed position.

6. Means for raising and lowering a sash in a 50 window frame comprising a threaded shaft, a slotted pipe surrounding said shaft, a bracket secured to the sash and penetrating said slotted pipe and threadably engaging said shaft, means 55 for driving said shaft comprising a housing having one of its ends surrounding the lower end of the shaft and rotatable on the shaft, a motor housing disposed on the end of the first housing, a motor in said motor housing, a train of gears 60 between the motor and said shaft and being disposed in said rotatable housing, whereby the position of the motor may be adjusted to fit window sills of various depths.

WILLIAM W. FULLER. 65
